UNITED STATES PATENT OFFICE.

JOSEPH HUTCHINSON, OF NEW YORK, N. Y.

MECHANICAL RESTAURANT-SERVICE.

1,215,536.

Specification of Letters Patent. Patented Feb. 13, 1917.

Application filed May 3, 1913. Serial No. 765,387.

To all whom it may concern:

Be it known that I, JOSEPH HUTCHINSON, of New York city, New York, United States of America, and temporarily residing at 5 Montreal, Quebec, Canada, have invented a new and useful Mechanical Restaurant-Service; and I do hereby declare that the following is a full, clear, and exact description of the same.

10 This invention comprises a mechanism for conveying trays or the like from the kitchen of a restaurant to the tables in the dining room of the latter and for returning the trays to the kitchen, the primary object 15 of the invention being to provide a mechanical service which will perform the function of human attendance at the tables of a restaurant.

Further objects are, first, to provide a conveyor for the trays, such conveyor being normally stationary and adapted to be operated to carry the trays to the tables; second, to indicate the position of the trays as they are being carried by the conveyor and to determine the arrival of the trays opposite to the tables; third, to move the trays from the conveyor to the tables and back to the conveyor; and fourth, to return the trays from the tables.

30 Further objects and features will be described in the following description and particularly pointed out by the appended claims.

For full comprehension, however, of my invention reference must be had to the accompanying drawings forming a part of this specification, in which similar reference characters indicate the same parts and wherein:

40 Figure 1 is a side elevation, partly broken away, of my mechanical device;

Fig. 2 is a plan view of the same with the top of the housing removed;

Figs. 3 and 4 illustrate the left hand side 45 of Figs. 1 and 2, respectively, and are drawn to a larger scale;

Fig. 5 is a detail of the gearing between the feed and return conveyor;

Fig. 6 is a perspective view of the means 50 for moving the tray to and from the tables;

Fig. 7 is an enlarged vertical section on line 7—7 Fig. 2 and showing in detail the mechanism illustrated in Fig. 6;

Fig. 8 is a perspective view of the trans-

ferring mechanism between the feed and return conveyers; and

Fig. 9 is an enlarged vertical section on line 9—9 Fig. 1 and looking in the direction of the arrow.

Briefly, my invention consists of a delivery conveyor extending from the kitchen to the dining room for carrying the trays to the tables in the latter; an arrangement for moving the trays from the delivery conveyor to the tables and back to the conveyor; a return conveyor located beneath the delivery conveyor for carrying the trays back to the kitchen; a device at the end of the delivery conveyor for lowering the trays therefrom to the return conveyor; a drive wheel operatively connected to and synchronously operating the conveyors and lowering device; and an indicator for determining the position of the trays as they are being carried by the delivery conveyor and arresting the movement of the drive wheel at different points in its rotation which correspond to predetermined points in the travel of the delivery conveyor.

I will now describe one form of my invention and it is to be understood that it may be constructed in any preferred manner with regard to details and arrangement of parts.

The mechanism illustrated in the drawings comprises an endless conveyor extending from the kitchen A (or room adjacent thereto) through the wall c thereof to the dining room B. A series of suitably spaced tables are arranged at each side of the conveyor and the length of the latter is dependent upon the number of tables employed.

The conveyor, which I will term the delivery conveyor, is level with the tops of the tables and consists of a pair of cables e passed around drums f, rotatively supported by standards g, the cables carrying transversely disposed slats f' which engage with the teeth h of sprocket wheels h' fixed at the ends of the drums f and by means of which engagement the conveyor is moved when the drums are rotated. A return conveyor is situated a suitable distance beneath and extended beyond the ends of the delivery conveyor and is of similar construction to the latter, being mounted upon drums e supported by the standards g. Rails j are

supported immediately beneath and longitudinally of the top portion of each of the conveyers by brackets k , the rails terminating just short of the drums of the conveyers and being adapted to sustain the weight of the trays carried by the latter.

The conveyers travel in opposite directions (see arrows Figs. 1 and 3) and I prefer to operate them by means of a wheel l , the shaft l' of which is rotatively supported by standards m and m' located at the kitchen end of the conveyers, the wheel being preferably rotated by hand although a motor or the like may be employed for this purpose. The periphery of the wheel l is of sufficient width to accommodate hand pieces n and teeth o , the latter having a drive chain p passed thereover which connects the wheel to a sprocket wheel q upon the shaft f' of one of the drums of the return conveyer. The return conveyer is moved in one direction by means of the chain connection therebetween and the wheel and movement is imparted to the delivery conveyer in an opposite direction (see arrows Fig. 3) by means of a sprocket wheel r upon the shaft f' , a sprocket wheel s upon a suitably supported short shaft t and a pair of intermeshing gears t' upon the short shaft t and the shaft f^2 of the delivery conveyer, respectively, (see Fig. 5).

A tray is placed upon the delivery conveyer and the operating wheel rotated by means of the hand pieces n to move the conveyer and carry the tray into the dining room. In order to determine when the tray has reached a position opposite the table for which it is intended I have employed an operating wheel the circumference of which is sufficiently greater than that of the drums f to enable a single revolution of the wheel to move the conveyer the full length of its travel, and in conjunction therewith have also provided means upon the operating wheel which can be adjusted so as to engage with any one of a series of stops which are placed at different points around and distinct from the wheel and which correspond to the different position of the tables along the conveyer.

For the purpose just mentioned of arresting the rotation of the operating wheel one of the side surfaces of the latter is provided with a series of radially disposed holes w while the standard m' is enlarged and constitutes a dial having a straight slot x radially disposed relatively to the wheel, and circular slots y leading from the straight slot concentrically with such wheel and being of the same number as the holes w . The holes w which may be equal in number to the tables employed each have one of the circular slots y opposite thereto and is identified with one of the tables by a number or the like, but if the tables at one

side of the conveyer are each disposed opposite one of the tables at the other side then it is only necessary to provide one hole for each pair of oppositely arranged tables. The series of holes are preferably repeated at suitable points upon the surface of the wheel so that a series can be readily brought opposite to the straight slot. A distinctive mark upon a stationary part such as stand 15 adjacent to the conveyer designates the point at which to place each of the trays upon the latter so that the travel of the trays will be the same in each case and the extent of each circular slot y corresponds to the distance of its respective table away from such starting point of the trays.

When the operating wheel is about to be rotated to convey a tray to the dining room one of the series of holes w is brought opposite the straight slot x and a removable plug 50 is inserted into that hole which is identified with the table the tray is intended for. The plug extends through the slot x and when the wheel is rotated such plug travels within that circular slot which is opposite to the hole containing the plug and engages with the end of the slot thus preventing further movement of the wheel and indicating that the tray is opposite the desired table. To warn the operator that the tray is approaching its destination I have located a pair of spring contacts 3 in each of the circular slots near the end thereof and have electrically connected such contacts, as at 4, with bells or lamps 5 so that when the plug, which may be of metal, passes between the contacts the electrical circuit is closed and the operator warned in time to prevent the rotation of the wheel being stopped suddenly and in a jarring manner. When the tray arrives opposite to the desired table the plug 50 is removed to permit of the operation of the conveyer for the disposal of other trays that have been placed upon the conveyer, it being preferred to employ a separate plug for each tray and insert such plug when the tray is placed upon the conveyer.

Each of the tables is provided with means for removing a tray from the conveyer to the table and back again, such means preferably consisting of a catch 6 which travels in a slot 6^a formed in the table and extending outwardly from the conveyer, the catch being supported within a longitudinally grooved rail 7 supported by brackets 8 a suitable distance beneath the slot and extending to a point adjacent to the conveyer. The catch 6 is moved to and from the conveyer by means of wires or the like, a wire 9 being attached to one side of the catch near the bottom thereof and extended away from the conveyer, passing over pulleys 10 to the kitchen, while a second wire 11 is attached to the opposite side of the catch and ex-

tends toward the conveyer and thence to the kitchen over pulleys 12.

The trays I prefer to employ each have a downturned edge 14, which, as the tray is placed upon the conveyer, is disposed to that side of the latter at which the desired table is situated. The normal position of the catch 6 is at a point adjacent to the conveyer as shown in full line Fig. 7 and in this position the edges 14 of the trays pass over the tops of the catches which latter are preferably formed with cross-pieces 5^a. When the tray is stopped opposite a table, the catch of the latter will be pulled away from the conveyer by the wire 9, the catch engaging with the downturned edge 14 and drawing the tray upon the table. When it is desired to return the tray to the conveyer the latter is stopped and the tray replaced thereon by pulling the catch toward the conveyer by means of the wire 11. The wires 9 and 11 of each table are passed through stands 15 at each side of the kitchen end of the conveyer and are provided with hand pieces 15^a, the wires of each table being distinguished from those of the other tables by numbers or the like.

It will be apparent that with a number of trays upon the conveyer certain of the trays 30 may be opposite to a table when a tray is being removed from the same and this is avoided by means of the plugs 50 which each indicate the position of its respective tray as it travels forward and consequently indicates by the position of a plug in one slot relatively to the termination of the other slots, when the space opposite to a table is not occupied, for example, if a plug is traveling in the slot identified with table 3 and 40 is opposite to the termination of the slot identified with table 2 it will be shown that the space opposite to such table 2 is occupied.

In order to have the conveyers and their mechanisms out of sight I prefer to inclose the dining room portion of the device within a housing 16 provided with openings opposite each table, the openings being covered by doors 17 hinged as at 17^a to swing outwardly and upwardly for the passage of a tray through the door opening, each of the doors being automatically opened and closed by means of an angle piece 18 upon the door, one arm of which angle piece extends 55 through an opening 19 in the housing and has a depending hook 20 thereon passed through a slotted bracket 20^a. The hook 20 is situated in the path of a rigid member 21 presenting at opposite ends bottom cam faces 60 22 and 23, respectively, such member being carried by a lateral arm 22^a upon the catch 6 and adapted to move with the latter through an opening 24 in the side of the housing. The bottom of the cam member 65 21 is on a lower level than the end of the

hook so that when the catch is moved away from the conveyer the cam face 22 will engage with the hook and draw the latter down thus opening the door, the hook passing along the straight lower edge of the member 21 which maintains the door in its open position. The length of the straight edge of the cam member is such that when the tray is upon the table and moving clear of the door opening the hook will pass from such straight edge and be engaged by the other cam face 23 which latter will gradually permit the hook to move up and the door to close under its own weight. When the tray is returned to the conveyer by means of the wire 11, the door is opened by the cam face 23 of the member 21 and closed by the cam face 22 as above described. The bracket 20^a prevents the depending arm from being simply swung out of the way of the cam member and it accommodates the slight swing of such hook caused by the angle piece when being moved to open or close the door.

When the tray is again upon the conveyer the operating wheel is rotated to carry the tray to the end of the delivery conveyer where it is lowered to the return conveyer by a device which I will now describe with particular reference to Figs. 8 and 9.

As mentioned herein the return conveyer extends beyond the ends of the feed conveyer and at each side of the dining room end of the former there is a pair of standards 25 supporting between them, longitudinally of the conveyers, upper and lower shafts 26 and 27, respectively. These shafts each carry sprocket wheels 28 and 29 connected in vertically disposed pairs by chains 28 and 29^a, respectively. The lower shaft 27 at each side of the conveyer is operatively connected to the return conveyer by means of a bevel gear 30 upon the shaft of the drum *a* and intermeshing with a bevel gear 31 upon the upper end of a vertical shaft 32 110 rotatively supported in bearings 33 and having a bevel gear 34 upon its lower end which intermeshes with a bevel gear 35 upon such lower shaft 27. The connection between the return conveyer and the shafts 27 causes the chains to move synchronously with the conveyers and in an inward and downward direction with relation to the same. The chains each carry outwardly projecting fingers 36 which are arranged in sets, that is to say the fingers carried by a chain on one side of the conveyer travel in horizontal line with fingers carried by the other chain and by the chains on the opposite side of the conveyer. The fingers 36 are hinged as at 30^a 120 to enable them to fold back upon the chain when they encounter an obstruction.

A pair of brackets 36^a extend from each side of the housing 16, over the shaft 26 to a point on the inner side of the latter, the 130

- inner ends of each of the brackets having a narrow strip 37 hinged thereto and yieldingly held in horizontal position level with the top of the feed conveyer by springs 38.
- 5 The strips 37 form a continuation of the delivery conveyer substantially the same length as a tray and are adapted to receive the latter as it passes from the conveyer, the weight of the tray being sustained by spring controlled trip hooks 39 supported by brackets 40 upon the standards 25. The hooks are slightly inclined and extend beneath the strips 37 and are adapted to be engaged by the forward end of the tray which displaces the hooks and permits the strips to drop and release the tray as seen in dotted lines Fig. 9. As the tray passes from the strips it is received by one of the sets of fingers 36, which latter lower it to the return conveyer.
- 10 The springs controlling the strips 37 and hooks 39 return these members to their former position ready to receive the next tray, the springs 38 being at a greater tension than those controlling the hooks 39 so that 15 the strips 37 are returned to their normal position in advance of the hooks and in readiness to have the latter engage beneath them.
- The return conveyer carries the tray to 20 the kitchen where it is removed from the conveyer, the continuation of the return conveyer beyond the delivery conveyer facilitating the removal of the tray from the former.
- 25 35. What I claim is as follows:
1. A mechanical restaurant service including a device having tray supporting mechanism moving in one direction in one plane to deliver the tray, such mechanism extending and moving the tray to a different plane and moving in another direction to return the tray, a table at the side of the mechanism and means for mechanically removing the tray from the conveyer to the table and 45 mechanically returning such tray to the conveying mechanism.
  2. A mechanical restaurant service including a conveyer adapted to carry a tray and means for operating the conveyer including 50 a rotatable member, a standard adjacent to the rotatable member and co-acting devices extending between said member and standard for indicating the position of the carried tray.
  3. A mechanical restaurant service including a conveyer adapted to carry a tray and means for operating the conveyer including 55 a rotatable member, a stationary member adjacent to the rotatable member, an indicating device upon one of said members and a projection upon the other of said members and adapted to engage with the indicating device to indicate the position of the carried tray.
  4. A mechanical restaurant service includ-
- ing a conveyer adapted to carry a tray, a rotatable member for moving the conveyer and means for indicating the position of the tray including a stationary member adjacent to the rotatable member and an electrical conductor upon each of the members, and adapted to engage to close an electrical circuit.
5. A mechanical restaurant service including a conveyer, an operating wheel supported adjacent to and operatively connected to one end of the conveyer, such operating wheel being of a size to move the conveyer the full length of its travel in one revolution and having a radially disposed series of holes therein, a standard having a series of circular slots therein, concentric with the operating wheel and each disposed opposite to one of the holes in the latter, the slots being of varying length to correspond to different points in the travel of the conveyer, electrical contacts in each of said slots and included in an open electrical circuit and a removable plug adapted to be inserted in one of said holes in the operating wheel, travel in one of the said slots and engage with the electrical contacts therein to close the circuit.
6. A mechanical restaurant service including a conveyer adapted to carry a tray, an operating wheel for the conveyer, a series of stops adjacent to the wheel and at varying points in its rotation and which correspond to varying points in the travel of the conveyer, and a projection carried by the operating wheel and adapted to be adjusted to engage with either of the said stops.
7. A mechanical restaurant service including a conveyer adapted to carry a tray, an operating wheel for the conveyer, a series of stops adjacent to the wheel, and at varying points in its rotation and which correspond to varying points in the travel of the conveyer, a projection carried by the operating wheel and adapted to be adjusted to engage with either of the said stops, and means for indicating the near approach of said projection to the stop to be engaged with.
8. A mechanical restaurant service including a conveyer, an operating wheel supported adjacent to and operatively connected to one end of the conveyer, such operating wheel being of a size to move the conveyer the full length of its travel in one revolution and having a radially disposed series of holes therein, a standard having a series of circular slots therein, concentric with the operating wheel and each disposed opposite to one of the holes in the latter, the circular slots being of varying length to correspond to different points in the travel of the conveyer, and a removable plug adapted to be inserted in one of the said holes in the operating wheel and travel in one of the said circular slots.

9. A mechanical restaurant service for conveying a tray from an ante-room to a dining room and including a series of tables in the dining room, a conveyer adjacent to and on a level with the table, operating means in the ante-room for moving the conveyer to carry a tray opposite to either of the tables, and mechanism for moving the tray between the conveyer and the tables including catches adjacent to each of said tables and adapted to respectively engage with the tray and means for reciprocating the catches transversely of the conveyer, including a length permanently connected to each of said catches independently of the others and extending to the ante-room. 10. A mechanical restaurant service including a table, a conveyer adjacent to and on a level with the table, operating means for moving the conveyer to carry a tray opposite to a table and mechanism for moving the tray between the conveyer and the table including a support extending from beneath the table toward the conveyer, guides spaced longitudinally of the support, a catch movably mounted upon said support and located between the guides and flexible lengths attached to the catch and extending in opposite directions therefrom, each length passing around one of said guides to a point spaced from the table. 11. A mechanical restaurant service including a table, a conveyer traveling adjacent to and on a level with the table, a housing for the conveyer and having an opening opposite to the table, a door normally closing such opening, operating means for moving the conveyer to carry a tray opposite to the table, and mechanism for moving the tray between the conveyer and the table through said opening and automatically opening and closing said door during the movement of the tray. 12. A mechanical restaurant service including a table, a conveyer adjacent to and on a level with the table, a housing for the conveyer and having an opening opposite to the table, a door normally closing such opening, an arm upon the door, a hooked member depending from the arm, a double cam member adapted to reciprocate transversely to the conveyer and engage with the hooked member and means for moving such double cam member. 13. A mechanical restaurant service including a table, a conveyer traveling adjacent to and on a level with the table, a housing for the conveyer and having an opening opposite to the table, a door normally closing such opening, a hooked member depending from the door, operating means for moving the conveyer to carry a tray opposite to the table, and mechanism for moving the tray between the conveyer and the table through said opening and automatically opening and closing such opening, a double cam member adapted to reciprocate transversely to the conveyer and engage with the hooked member and means for moving such double cam member. 14. A mechanical restaurant service including a delivery conveyer adapted to carry a tray in one direction, a return conveyer on a different level to the delivery conveyer and adapted to carry the tray in another direction, a conveyer adapted to receive the tray directly from the delivery conveyer and carry such tray to the return conveyer and operating means for the conveyers. 15. A mechanical restaurant service including a delivery conveyer adapted to carry a tray in one direction, a return conveyer on a different level to the delivery conveyer and adapted to carry the tray in another direction, a conveyer adapted to receive the tray directly from the delivery conveyer and carry such tray to the return conveyer and operating means for synchronously operating the conveyers. 16. A mechanical restaurant service including a delivery conveyer adapted to carry a tray in one direction, a return conveyer beneath the delivery conveyer and adapted to carry the tray in another direction, a conveyer adapted to receive the tray directly from the delivery conveyer and lower such tray to the return conveyer and operating means for the conveyers. 17. A mechanical restaurant service including a delivery conveyer adapted to carry a tray in one direction, a return conveyer beneath the feed conveyer and adapted to carry the tray in an opposite direction, mechanism for lowering the tray from the feed conveyer to the return conveyer including a pair of spring controlled strips extending from the end of the feed conveyer, spring trip hooks supporting the strips, a pair of chains at each side of the strips, such chains moving downwardly from the delivery conveyer to the return conveyer, outwardly extending fingers carried by the chains, and means for operating the conveyers and the said chains. 18. The combination with a series of tables, of a delivery conveyer traveling adjacent to and on a level with the tables and adapted to carry a tray in one direction, a return conveyer beneath the delivery conveyer and adapted to convey the tray in an opposite direction, a device for lowering the tray from the delivery conveyer to the return conveyer, a housing for the conveyers and lowering device, such housing having openings in the sides thereof and opposite to the tables, doors for such openings, means for synchronously operating the conveyers

and the lowering device, and a mechanism at each table for moving the trays between the delivery conveyer and the tables through the said openings and for opening and closing the doors, such mechanisms being operated from a point distant from the tables.

In testimony whereof, I have signed my

name to this specification, in the presence of two subscribing witnesses.

JOSEPH HUTCHINSON.
